(57) **CLAIM**

The ornamental design for a solar lamp, as shown and described.

DESCRIPTION

FIG. 1 is a first perspective view of a solar lamp showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion in FIG. 2. The dash-dash broken lines in the figures illustrate portions of the solar lamp. The dash-dot broken-line circle, which illustrates the bounds of the enlarged view, and the solid-arc lead line in FIG. 2, together represent a detail callout. The broken lines form no part of the claimed design.
